UNITED STATES PATENT OFFICE.

MORITZ FELDMANN, OF NEW YORK, N. Y.

DESIGN FOR A CLASP FOR HOSE-SUPPORTERS.

SPECIFICATION forming part of Design No. 19,857, dated May 27, 1890.

Application filed March 1, 1890. Serial No. 342,302. Term of patent 7 years.

To all whom it may concern:

Be it known that I, MORITZ FELDMANN, of the city, county, and State of New York, a citizen of the Empire of Austria-Hungary, 5 have invented a new and original Design for Hose-Supporting Clasps, of which the following is a specification.

This invention relates to a design for a clasp for hose or stocking supporters, where-
10 by these clasps are made ornamental and attrac-
tive in appearance; and the invention
consists of a design for a hose-supporting
clasp in which the curved sides of the clasp
are scalloped at the outer and inner edges
15 while the top cross-bar is made plain.

The nature of my design is fully shown in
the accompanying drawing, to which refer-
ence is made.

A in the drawing represents a clasp for
20 hose or stocking supporters of that class in
which two curved sides *a* terminate in a cen-
trally-slitted lower part *b* and are connected
at their upper ends by a transverse top bar
25 *d*. The inner and outer edges of the curved
sides *a* are scalloped, the scallops at the outer

edges extending to the lower end of the clasp
A, while the scallops at the inner edges ter-
minate at the point where the slit *d* of the
lower part *b* commences. The top bar *b* is
not scalloped, but remains plain, as the elas-
tic supporting-strap of the clasp is to be ap-
plied thereto. 30

Having thus described my design, I claim as
new and desire to secure by Letters Patent—

The design for a clasp for hose-supporters, 35
consisting of the curved sides *a*, the centrally-
slitted lower part *b*, the top bar *d*, and scal-
lops on the outer and inner edges of the
curved sides *a*, the scallops on the outer edges
extending to the lower end of the clasp and 40
the scallops on the inner edges terminating
at the beginning of the slit, substantially as
shown and described.

In testimony that I claim the foregoing as
my invention I have signed my name in pres- 45
ence of two subscribing witnesses.

MORITZ FELDMANN.
